UNITED STATES PATENT OFFICE.

EUGENIO PLANCHAT, OF TURIN, ITALY.

PROCESS FOR THE QUICK DRYING OF CINEMATOGRAPHIC FILMS AND THE LIKE.

1,232,077.

Specification of Letters Patent.

Patented July 3, 1917.

Application filed November 18, 1915. Serial No. 62,201.

To all whom it may concern:

Be it known that I, EUGENIO PLANCHAT, engineer, a citizen of France, residing at Turin, Italy, have invented certain new and useful Improvements in Processes for the Quick Drying of Cinematographic Films and the like; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of the present invention is a process and device for the quick drying of cinematographic films, and the like.

The drying of cinematographic films was till now obtained by having said films cross a hot air drying room. As, however, the quantity of liquid adhering to the film on its coming out from the baths and the quantity imbuing the layer of gelatin is considerable, the result was that the time required by the operation of drying was very long, being necessary for the film to have a long run within the drying room, great dimensions being required for the latter, before all the liquid was dried.

Now, grace to the present invention, and to the purpose to reduce the duration of the process of drying and the dimensions of the drying room in a remarkable way, the whole of the liquid adhering to the film and the greatest part of the liquid imbuing the layer of gelatin are removed before its entering the drying room. Such an elimination is obtained by submitting the film, when coming out from the baths, to an energetic compressing action which is obtained by having the film pass through a bath of mercury, or fluid amalgam, placed in a vertical vessel, having a convenient height, divided, by means of an intermediate wall or division, into two compartments, communicating between each other at the bottom of the said vessel, one of which compartments is destined to contain the descending wet portion of the film, and the other the nearly dry portion of the ascending film. Owing to the considerable specific weight of mercury, or fluid amalgam, the portion of wet film descending into the first compartment, under-

which may be elevated to any degree of pressure, by suitable choosing of the height of the mercury or fluid amalgam bath contained in the vessel. Under the action of such a pressure, the whole of the liquid adhering to the film and the greatest part of the one imbuing the layer of gelatin is removed and rises to float on the surface of the bath of mercury, or fluid amalgam, in the first compartment, whence it goes out through an overflow pipe. The film, which is nearly fully dry, when coming up out of the second compartment, is conveyed, in the usual way, into and runs for a short run, through a usual small sized hot air drying room where drying is completed within a very short time.

From the above it will be readily understood that apparatus for effecting the drying in accordance with what has been above stated may be given many forms.

The accompanying drawing shows schematically and by way of example one of many forms of such an apparatus:

In such a drawing, —1— represents the vertical vessel destined to contain the bath —2— of mercury, or fluid amalgam. The said vessel is divided into two compartments —1', 1''— by means of the intermediate wall —1a— descending nearly as far as the bottom of the vessel itself. The film —3—, conveyed and guided by means of rollers —4—, which are suitably placed, is run through the bath —2— of mercury, or fluid amalgam, putting same, by any means, into motion in the direction shown by the arrows. The portion of the wet film which descends along the first compartment, is submitted, by the action of the mercury, or fluid amalgam, to an energetic compression, which is proportional to the reached depth, so that the whole of the liquid adhering to the film and the greatest part of the liquid imbuing the layer of gelatin, is removed. Such a liquid comes up and floats in —5— on the surfaces of the mercury, or fluid amalgam, in the compartment —1'—, whence it is discharged through the overflowing pipe —6—. The nearly dry film, coming up along the compartment —1''—, comes outside and is conveyed to any drying room —7— where drying is completed.

Claims:

1. The method of drying cinematographic films or the like which consists in passing a wet film downward through a column of

unheated mercury, or fluid amalgam, of a height capable of exerting sufficient pressure on the film to remove the liquid adhering thereto and to squeeze therefrom the greatest part of the liquid imbuing the film.

2. The method of drying cinematographic films or the like which consists in passing a wet film downward through a column of unheated mercury, or fluid amalgam, of a height capable of exerting sufficient pressure on the film to remove the liquid adhering thereto and to squeeze therefrom the greatest part of the liquid imbuing the film, and draining off from the top of the column the liquid separated from the film.

3. The method of drying cinematographic films or the like, which consists in passing a wet film downward through one of two columns of unheated mercury, or fluid amalgam, of a height capable of exerting suffi-

cient pressure on the film to remove the liquid adhering thereto and to squeeze therefrom the greatest part of the liquid imbuing the film, drawing the dried portion of the film upward through the second vertical column which is so separated from the first column as to prevent liquid extracted from the film in the first column from contacting with the film in passing from the top of the second column, and draining off from the top of the first column the liquid as it accumulates thereon.

In testimony that I claim the foregoing as my invention, I have signed my name in presence of two subscribing witnesses.
